UNITED STATES PATENT OFFICE.

LEVI W. STOCKWELL, OF CLEVELAND, OHIO, ASSIGNOR TO THE CLEVELAND ELECTRIC MOTOR COMPANY, OF SAME PLACE.

SWITCH FOR ELECTRIC-MOTOR AND OTHER CIRCUITS.

SPECIFICATION forming part of Letters Patent No. 326,603, dated September 22, 1885.

Application filed June 4, 1884. (No model.)

To all whom it may concern:

Be it known that I, LEVI W. STOCKWELL, of Cleveland, in the county of Cuyahoga, in the State of Ohio, have invented certain new and useful Improvements in Switches for Motor and other Circuits, of which the following is a specification.

My improved boards are especially designed for use in the circuits of dynamo-electric machines containing electric motors, lamps, or other appliances, or a combination of them.

The object of the invention is to maintain a uniform resistance in a line at each motor, so that the electro-motive force will be constant, whether the motor is running or is at rest.

In the accompanying drawings, Figure 1 is a plan view of the face of the board. Fig. 2 is merely a view of the bottom plate or under side of the switch-box. Fig. 3 is a plan view with the under plate of the switch-box removed. Fig. 4 is an interior plan view of the supplemental resistance-bars. Fig. 5 is a diagram illustrating the connections and circuits. Fig. 6 is a vertical longitudinal section on the line 6 6 of Fig. 1, and Fig. 7 is a transverse section showing merely the two sets of resistance-bars.

Referring for the present solely to the diagram view, Fig. 5, the main line L enters the instrument at the binding-post A, which is in electrical connection with a plate, a, which is in electrical communication with another binding-post, A', and with a contact-button, A''. The main resistance R is connected at this side of the instrument directly with the post A, with which the main line is connected, and the opposite side of the resistance R is connected with a post, B, through which the main line L' leaves the instrument. This post B is in contact with a plate, b, which is also in electrical connection with a binding-post, B', and a contact, B'', the arrangement being the same on both sides of the instrument. The resistance R is composed of a series of resistance-bars, r, preferably of carbon, which are connected in the ordinary way, as clearly illustrated in the figure. From the post A' a line, s, runs through a supplementary resistance, S, also composed of connected resistance-bars, preferably of carbon, and from

thence the line s runs to the heel of a pivoted switch-finger, D, and from thence by line m, through a motor, M, or other appliance, to the binding-post B' on the plate b. The resistance-bars r are connected, as shown, in a continuous series, and on the side next to the switch-finger D the loop of wire connecting the ends of each pair of bars is electrically connected with one of a series of contacts, c' to c'', which are traversed by the finger D. The current which enters the instrument at A, will of course divide inversely, according to the resistance of the loop-circuits through the resistance S and the resistance R. With the contact-finger in the position shown in the diagram—that is, on the contact c''—a part of the current entering at A would pass through S and part would enter the resistance R. The current entering the resistance R, after passing through the first four resistance-bars r, would unite with the current passing through the resistance S at the switch-finger D, and the current would then pass through the motor M and through the remaining bars of the resistance R, according to the relative resistance of the two paths. The current which passes through the remaining resistance-bars of the resistance R to the binding-post B would there unite with the current which had passed through the motor M, and go to line L'. If the switch-finger D be moved from the contact c'', so as to rest on the contact A'', the main course of the current would be directly through the finger D and motor to the line L'. No current would pass through the resistance S and little or no current through the resistance R; but if the switch-finger D be moved toward B'', at each succeeding contact in its course the current passing directly through the motor M will be reduced, and there will be more current through the resistance S. As before remarked, the currents which unite at the finger D will pass through the motor and through the remaining resistance-bars of the resistance R, according to their relative resistances, and as the finger D is moved toward the contact B'' the number of resistance-bars in the branch of the circuit through the finger D and R would be decreased, and a relatively greater current would pass through said bars to the binding-post B,

thus reducing the amount of current passing through the motor. If the movement of the finger D be continued until it reaches the contact B^2 , as shown by the dotted lines in the 5 diagram, the current will cease to pass through the motor M, but will pass through R and S proportionately to their resistances. The resistance of S should be the same as that of the motor M, and the resistance of R should be so 10 proportioned that when the finger D is on the contact A^2 the motor will run with the greatest power desired. The sections 1 2 3 4 5 6 7 8 of the resistance R have each the same resistance as the motor. When the finger D is 15 on the contact A^2 , then eight parts of the current will pass through the motor M and one part through the resistance R; but if the finger D rests on the contact c^2 half the current will pass through section 8 of the resistance R and 20 the other half through the motor M. When the switch-finger rests on the contact B^2 , as shown in dotted lines, eight parts of the current received at A will pass through the resistance S and one part through the resistance 25 R, cutting the motor entirely out. Whatever may be the position of the finger D, therefore, the internal resistance of the instrument and the amount of current leaving it at the post B are the same. The motor or other appliance 30 may therefore be started, stopped, and run without creating variations of electro-motive force in the circuit. As before remarked, the electrical resistance of S M and the sections 1 to 8 of the main resistance R are equal, and I 35 have in the drawings indicated this by marking each of them 10.

Fig. 1 represents the face of the switch-board, and shows the finger D drawn normally over to the contact B^2 by spring d. In this 40 position the motor is cut out of circuit, as described. By means of a cord or other suitable device, d', which may be actuated and held in position by a foot-lever or any other desirable means, the lever may be drawn against the 45 force of the spring over the contact-buttons to throw the motor into operation and vary the power with which it may be driven. The different wires shown in Fig. 1 are lettered to correspond with those in the diagram, and the 50 connections will be plain.

The main resistance R is preferably arranged in an iron case, which is perforated, as indicated in Figs. 1 and 2, to permit the free circulation of air. The supplemental resistance r is mounted in a supplemental box or case, (shown in Figs. 4, 6, and 7,) which is bolted to the under side of the main switch-box.

The carbon bars are provided with metal 55 sockets e at their ends, and with metal fingers e' projecting from these sockets, by means of which the bars are mounted on cross-pieces F in the case, which cross-pieces are made of wood or other suitable insulating material. 60 The bars are held in place by staples, which 65 are driven down over the fingers e'. The bars

are electrically connected alternately at opposite ends with the following bars in the series. This is preferably done by small plates e², which may be screwed to the socket-pieces e. This construction is clearly illustrated in Fig. 3.

The arrangement of the bars in both the main resistance R and the supplemental resistance S is substantially the same. In the 70 supplemental resistance, however, as shown in Fig. 4, single socket-pieces e are provided for the reception of the ends of the adjoining bars. This manner of connecting resistance-bars, however, is of course well understood, 80 and it is well known the current enters a bar at one end and is caused to traverse successively through all the bars in the series.

The metal sockets or end pieces, e, may be electroplated on the ends of the bars, if desired.

The boxing or casing G of the main resistance R is formed of two sections, which are bolted together. The resistance-board thus constructed may be secured in the desired position in any suitable well-known way.

Eight pairs of bars only are shown in the diagram, Fig. 5, while ten are shown in Fig. 3, and in the latter figure one pair of bars on each side of the series is unconnected directly 95 with any contact swept by the finger D. This latter construction of course causes a greater change in the relative resistance of the branch circuits at those two points. Where ten pairs of bars are used, as in Fig. 3, an 100 additional contact for each bar may be placed in the series C' and C²; or the additional pairs of bars may be omitted.

I prefer to construct the instrument in accordance with the diagram view, Fig. 5—that 105 is, with each pair of bars connected with a contact, as shown.

I claim as my invention—

1. The combination, substantially as set forth, of a main line, a resistance, S, an electro-motor or other instrument, devices, as described, for varying the resistance of the branches of the circuit, and the resistance R, which is connected up in sections, as described, the resistance of each of said sections 115 and of the supplemental resistance S being equal to that of the motor or other instrument.

2. The combination of the main resistance R, the contacts c^2 to c^2 , connected with the sections thereof, the lever which traverses them, the conducting-plates a b on each side of said resistance, the binding-posts A A' and B B', and the contacts A^2 B^2 on said plates, the motor, the supplementary resistance, and circuits 120 and connections, as set forth.

In testimony whereof I have hereunto subscribed my name.

LEVI W. STOCKWELL.
